WITNESS

UNITED STATES PATENT OFFICE.

ABEL MILLER AND PHILLIP MILLER, OF HARRISONBURG, VIRGINIA.

SAFETY-CABINET.

1,382,527.

Specification of Letters Patent. Patented June 21, 1921.

Application filed March 13, 1920. Serial No. 365,539.

To all whom it may concern:

Be it known that we, ABEL MILLER and PHILLIP MILLER, citizens of the United States, residing at Harrisonburg, in the county of Rockingham and State of Virginia, have invented new and useful Improvements in Safety-Cabinets, of which the following is a specification.

This invention relates to a container for receiving bottles of milk and the like and the principal object of the invention is to provide means for automatically locking the door of the container after the article has been placed therein so that it will be impossible to remove the article without unlocking the door.

Another object of the invention is to provide means for preventing the door from being locked as long as the container is empty.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:—

Figure 1 is a front view of the invention.

Fig. 2 is a longitudinal section thereof.

Fig. 3 is a cross section.

Figs. 4 and 5 are detail views.

In these views 1 indicates a casing, made of any suitable material and of any desired shape. This casing has an opening in its front which is closed by a door 2 which is hinged to the casing and is normally kept closed by the spring 3. The door carries a spring lock 4 which is of any desired type and the latch of which is retracted by a key. The casing is provided with a false bottom 5 which is normally held in spaced relation to the bottom of the casing by the springs 6, said springs being riveted at their centers to the main bottom and having their ends supporting the false bottom. A channel bar 7 is secured to one side of the casing, adjacent its front, by the flange 8 being riveted, or otherwise secured to said side and this bar is provided with a keeper opening 9

for receiving the latch bolt of the lock and thus lock the door in closed position. However, the latch bolt is prevented from entering said opening when the false bottom is in raised position by reason of the fact that a channel bar 10, slidably mounted in the channel of the bar 7, closes said opening and prevents the latch bolt from entering. Thus the door may be opened at any time against the action of its spring. As soon as the milk bottle or other article is placed in the casing its weight will depress the false bottom 5 and as the channel bar 10 has its lower end secured to this false bottom, said bar will be lowered also and its upper end will uncover the keeper opening 9 and permit the latch bolt to enter said opening and thus lock the door in closed position. In order to remove the milk bottles from the casing, the door may be opened by a key inserted in the keyhole in the lock. The rear of the case may be provided with perforated ears 11 for permitting the same to be fastened to a suitable support.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:—

1. A device of the class described comprising a casing having an entrance opening, a door for said opening, spring means for normally holding the door in closed position, a key operated spring lock for said door, a member for preventing the bolt of the lock from engaging its keeper and a spring supported receiving shelf in the casing connected with said bar and moving the same away from the keeper when an article is placed on the shelf.

2. A device of the class described comprising a casing having an entrance opening, a spring actuated door closing said opening, a channel member connected with the inner wall of the casing and having a keeper opening therein, a key operated spring lock carried by the door and having its bolt adapted to engage said keeper opening, a spring sup-

ported false bottom in the casing and a bar connected therewith and slidably mounted in the channel member with its upper end normally closing the keeper opening and 5 preventing the locking of the door, said end uncovering the keeper opening to permit the lock bolt to engage said opening when an

article is placed on the false bottom to depress the same.

In testimony whereof we affix our signatures.

ABEL MILLER.
PHILLIP MILLER.
